UNITED STATES PATENT OFFICE

142,172

DESIGN FOR A MECHANICAL DOLL

Lucretia Q. MacCallum, Beverly Hills, Calif.

Application April 3, 1945, Serial No. 118,842

Term of patent 7 years

(Cl. D34—15)

To all whom it may concern:

Be it known that I, Lucretia Q. MacCallum, a citizen of the United States of America, residing in the city of Beverly Hills, in the county of Los Angeles, State of California, have invented a new, original, and ornamental Design for a Mechanical Doll, of which the following is a specification, reference being had to the accompanying drawing forming a part thereof.

Fig. 1 is a perspective view of a mechanical doll showing my new design, with the hair of the doll in normal position;

Fig. 2 is a perspective view similar to Fig. 1, but with the hair in raised position;

Fig. 3 is a front elevational view of the mechanical doll shown in Fig. 1; and

Fig. 4 is a rear elevational view thereof.

I claim:

The ornamental design for a mechanical doll, substantially as shown and described.

LUCRETIA Q. MACCALLUM.
